UNITED STATES PATENT OFFICE

1,922,530

PIANO

Frank P. Dell and William Freeman,
Philadelphia, Pa.

Application August 25, 1931. Serial No. 559,208

8 Claims. (Cl. 84—183)

This invention relates to a piano and has particular reference to the provision of an improved cover for the strings and action of a piano specifically designed to act as an auxiliary sounding surface.

As is well known, the strings and action of pianos, particularly grand pianos, become rapidly covered with dust with impairment of their tonal qualities. It is, accordingly, one object of the present invention to provide a protective cover of a type which is particularly useful in grand pianos which are frequently left with their covers raised.

Another object relates to the provision of covering means capable of acting as an upper sounding board.

Further objects of the invention relating to the provision of an arrangement which will not interfere with tuning, and relating to details of construction will become apparent from the following description, read in conjunction with the accompanying drawing, in which:

Fig. 1 is a plan view of one modification of the invention, the piano lid being removed;

Fig. 2 is a vertical section on the plane indicated by line 2—2 of Fig. 1;

Fig. 3 is a vertical section on the plane indicated by line 3—3 of Fig. 1; and

Fig. 4 is a vertical section on the plane indicated by line 4—4 of Fig. 1.

The piano of generally standard construction to which the invention is applied is designated 2 and includes the usual sounding board 4 and string plate 6 which carries the usual arrangement of tensioned strings.

Above the string plate 6 is located a frame 8 conforming in shape to the interior of the piano. This frame 8 which terminates forwardly substantially coextensively with the sounding board 4, as indicated in Fig. 4, supports the stretched fabric cover 10 consisting of woven fabric such as linen or canvas, preferably impregnated with a varnish such as airplane "dope" or the like which imparts such stiffness thereto as to enable it to vibrate and thereby act as an auxiliary sounding board. The frame is held in raised position through the use of brackets 12 carrying pointed pins 14 which rest on the sounding board, passing, where necessary, through suitable openings 15 in the string plate 6. Soft beading 16 surrounds the frame 8 where it lies adjacent the walls of the piano so as to maintain it spaced from the walls and prevent the transmission of vibrations from the stretched cover 10 to said walls. The points on pins 14 prevent relative

movements between the frame 8 and the sounding board.

At its front end, the frame 8 is grooved as at 18 to clear the struts of the string frame, with which it should not contact. Since it terminates at the front end of the sounding board it does not interfere with the tuning.

The music rack 22 has a portion 24 extending rearwardly over the front of frame 8 without contacting therewith. The rack is removably secured in position by the provision of extensions 26 which rest in sockets in the side walls of the piano frame. The lid 20 is arranged to cover the piano in the usual fashion.

It will be obvious that numerous changes may be made in details of the invention without departing from the spirit thereof as defined in the following claims. For example, the cover 10 may consist of a number of separate pieces of fabric carried by one or more frames.

What is claimed is:

1. In combination with a piano having a frame, strings supported therein, and a sounding board extending adjacent the strings on one side thereof, a tone sustaining, stretched and stiffened fabric extending adjacent the strings on the opposite side thereof.

2. In combination with a piano having a frame, strings supported horizontally therein, and a sounding board extending below the strings and adjacent thereto, a cover for the strings consisting of a tone sustaining, stretched and stiffened fabric extending thereover.

3. In combination with a piano having a frame, strings supported therein, and a sounding board extending adjacent the strings on one side thereof, a tone sustaining, stretched and stiffened fabric extending adjacent the strings on the opposite side thereof, and means insulating the fabric against transmission of vibrations to or from the piano frame.

4. In combination with a piano having a frame, strings supported horizontally therein, and a sounding board extending below the strings and adjacent thereto, a cover for the strings consisting of a tone sustaining, stretched and stiffened fabric extending thereover, and means insulating the cover against transmission of vibrations to or from the piano frame.

5. In combination with a piano having a frame, strings supported horizontally therein, and a sounding board extending below the strings and adjacent thereto, a cover for the strings consisting of a tone sustaining, stretched

and stiffened fabric extending thereover, said cover being carried by the sounding board.

6. In combination with a piano having a frame, strings supported horizontally therein, and a sounding board extending below the strings and adjacent thereto, a cover for the strings consisting of a tone sustaining, stretched and stiffened fabric extending thereover, said cover being supported by a frame carried by the sounding board by means of pins, secured to the fabric supporting frame and pointed at their lower ends, resting on the sounding board.

7. In combination with a piano having a frame, strings supported horizontally therein, and a sounding board extending below the

strings and adjacent thereto, a cover for the strings consisting of a tone sustaining, stretched and stiffened fabric extending thereover, the cover terminating forwardly substantially coextensively with the sounding board.

80

8. In combination with a piano having a frame, strings supported horizontally therein, and a sounding board extending below the strings and adjacent thereto, a tone sustaining cover for the strings capable of sustained vibration at musical frequencies, and means insulating the cover against transmission of vibrations to or from the piano frame.
